UNITED STATES PATENT OFFICE.

ANTHONY AUGUST TUBBS, OF HAMMOND, INDIANA.

RAZOR-BLADE POCKETKNIFE.

Application filed March 3, 1921. Serial No. 449,288.

To all whom it may concern:

Be it known that I, ANTHONY A. TUBBS, a citizen of the United States, and a resident of Hammond, in the county of Lake and 5 State of Indiana, have invented a new and useful Improvement in Razor-Blade Pocketknives, of which the following is a full, clear, and exact description.

My invention relates to improvements in 10 pocket knives, and it consists in the combinations, constructions and arrangements herein described and claimed:

An object of my invention is to provide 15 a device of the character described in which a cutting blade may be sheathed within a combined handle and sheath when the device is not in use and extended at will to permit the use of the device in performing the functions for which intended.

20 A further object of my invention is to provide a device of the character described in which a safety razor blade of a well known type is detachably held in position to serve as the cutting blade of the device.

25 A further object of my invention is to provide a simple inexpensive device of the type described in which razor blades that would otherwise be discarded are utilized.

30 A further object of my invention is to provide a device of the type described that is simple in construction and operation, and thoroughly practical commercially.

Other objects and advantages will appear 35 in the following specification, and the novel features of the invention will be particularly pointed out in the appended claim.

My invention is illustrated in the accompanying drawings, forming part of this application, in which

40 Fig. 1 is a plan view of a blank used in forming a portion of the device,

Fig. 2 is a similar view of the blank used in forming another portion of the device,

Fig. 3 is a plan view of the device,

45 Fig. 4 is a similar view of the reversed side thereof showing a blade holding clip of the device partly withdrawn from its case.

In carrying out my invention, I make use 50 of a substantially rectangular flat sheet 1 of a light metal or similar material, as shown in Fig. 1. I provide a combined handle and sheath by folding an end extension 2 of the sheet 1 along the line *a*, a side portion 3 along the line *b*, and the opposite side portion 4 along the line *c* into the positions

shown in Fig. 4, thereby forming a combined handle and case or sheath that is closed at one end and has a pocket or bayonet slot adapted to receive a blade holding clip 5. 60 The latter is shown in its developed form in Fig. 2 and is bent intermediately along the line *d* to provide spring clamping arms 6 and 7 that are approximately parallel with one another. The clamping arm 7 is fashioned with a recess 8 in its inner wall adapted to receive an end portion of a safety razor blade 9 of a well known type and being provided with an upstanding stud 10 that fits an opening 11 that is ordinarily provided 70 in the razor blade 9. The arm 6 of the clip is fashioned with spaced apart parallel raised portions 12 adjacent its end and these raised portions bear against the razor blade 9 to firmly maintain the latter in position 75 on the stud 10 and between the arms 6 and 7 when the clip 5 has been retracted in the combined handle and sheath, as illustrated in Fig. 3.

It will be noted that the body portion of 80 the sheet 1 has a longitudinally extending slot 13 therethrough and extending from adjacent one end approximately half the length of the sheet. A similar slot 14 is provided in the side portion 4 and this slot 85 extends from a point adjacent the opposite end of the sheet 1 to a point beyond the transverse middle line of the sheet so that the combined handle and sheath has slots in the opposite side walls thereof that have portions in registry. The arm 6 of the blade holding clip is formed with a threaded opening 15 adapted to receive a screw 16 that is projected through the slot 13 and is movable 90 therealong.

95 From the foregoing description of the various parts of the device, the operation thereof may be readily understood. The blade 9 is extended beyond the end of the combined handle and sheath or case by 100 grasping the screw 16 and moving the same to the forward end of the slot 13. The blade holding clip is formed of a material having spring qualities and the width of the pocket of the combined handle and sheath is such as to insure a snug fit of the blade holding clip therewithin. Consequently, pressure is applied against the arms 6 and 7 so that the razor blade 9 is firmly clamped therebetween and may be used in 110 performing the function for which the device is intended. When it is desired to re-

place the blade 9 with another blade, the screw 16 is removed from the threaded opening 15 and inserted within the slot 14 so that the end thereof contacts with the end 5 of the blade holding clip 5. The latter is then ejected or partly ejected from the pocket of the combined handle and sheath by moving the screw 16 along the slot 14, as 10 illustrated in Fig. 4. The arms 6 and 7 may then be moved apart and a new blade substituted.

When the device is not in use the blade may be retracted by moving the screw 16 along the slot 13 toward the rear end thereof 15 until the blade is entirely sheathed within the handle as indicated by the dotted lines in Fig. 3. The device may then be carried about in the pocket of a garment, such as a vest pocket, without danger of injury to the garment, and can be placed 20 in operative condition quickly and easily when it is desired to use the same. The device is particularly suitable for use in cut-

ting operations where it is essential that the blade be very sharp and not necessary that 25 a very strong blade be used. The device can be manufactured cheaply and makes for economy in that the blades used therein and served the purpose for which originally intended and would otherwise be discarded. 30

I claim:

A device of the type described comprising a U-shaped blade receiving member having two sides adapted to grip an ordinary razor blade therebetween, one of said sides 35 being indented to snugly receive one side of the blade adjacent to one end thereof, and the other side having projections adapted to engage with the blade, a blade holder adapted to receive said member, said holder having a slot in each side thereof, and a screw removably carried by said member and being adapted to slide in either of the slots.

ANTHONY AUGUST TUBBS.
